ICE TRAY

Logan L. Mallard, Norfolk, Va., assignor of one-half to H. Clay Hofheimer, II, Norfolk, Va.

Application April 1, 1944, Serial No. 529,098

10 Claims. (Cl. 62—108.5)

1

This invention relates to ice forming apparatus or ice cube trays, and more particularly to a tray having means for automatically releasing the ice cubes from the tray after the ice is frozen and the tray is taken from the refrigerator.

It is an object of the invention to provide an ice tray which will more positively and uniformly eject the cubes when the tray is taken from the ordinary household refrigerator.

A further object of the invention is to provide a simple, inexpensive, practical, device of the above character.

The invention is intended to avoid the necessity for using levers or other extraneous mechanical devices for releasing the cubes for greater convenience.

Briefly stated, the invention includes the combination of spring means and heat operated means for distorting or moving a wall or wall portion forming an ice cube cell to eject the cube and one or more of which may be combined to provide an ice tray.

The foregoing and other objects and advantages will become apparent in view of the following description taken in conjunction with the drawings, wherein:

Figure 1 is a perspective of an ice tray illustrating one application of the invention;

Fig. 2, a section on the line 2—2 of Fig. 1;

Figs. 3 and 4, plan and side views respectively of a mounting disc and coil springs for application beneath a cube cell;

Fig. 5, a transverse section similar to that of Fig. 2, but with a different type of spring means beneath the cube cells;

Fig. 6, a multiple tempered spring unit;

Fig. 7, a section on the line 7—7 of Fig. 5; and

Fig. 8, a transverse section of a tray similar to those of Figs. 1, 2, 5 and 7, but with the bottoms of the cube cells corrugated and in physical contact with the bottom of the tray.

Referring to the drawings, the tray of the present invention consists of top 9 and bottom sections 10 adapted to have intimate contact with the upper surface of a freezing shelf of a household refrigerator or other freezing surface, and accordingly has a substantially flat under surface. For strength the bottom may have corrugations or crimped portions 11 extending longitudinally and transversely thereof or in any other desired manner. The bottom is also provided with a marginal upstanding flange 12 adapted to form a joint with the outer side wall 13 of the main body or top section of the tray. This main body or top section of the tray may be of stamped

2

sheet metal or other good conduction material with depressed wall portions 14 providing cube cells or pockets for water or other material to be frozen. As shown the walls forming the pockets or cube cells have separate bottoms 15 with their edges spun over the lower extremity of the depending walls 14, or otherwise intimately secured thereto. In order to facilitate the removal of ice from the cube cells or ice pockets the walls 14 are preferably tapered or uniformly enlarging from bottom to top of the cells, thus providing cells larger at the top than at the bottom so that ice may be discharged more easily.

The bottom 15 of the cube cell or chamber in which water is adapted to be frozen to form ice is preferably thinner than the side wall so that it can be readily flexed. In order to provide this flexing action the tray is constructed in a manner to provide a closed chamber about the exterior of each cube cell and between the cells and the outer walls and bottom of the tray. This chamber is filled with a volatile substance and at a temperature and pressure such that when the tray is taken from its refrigerating environment such as the cooling unit of a household refrigerator at a temperature below 32° Fahrenheit into the atmosphere at 70° or higher, heat will flow through the walls of the tray and heat the gas thereby causing it to expand and exert pressure on the most easily flexed portions of the tray, which according to the construction of the tray are the bottoms 15 of the ice cube cells. The tray may be provided with an extended end portion 21 in accordance with the volume of expandable fluid desired to be maintained within the chamber of the tray.

In order to supplement this gas expansion mechanical spring means may be employed. This spring means may include coil springs 16 of which, as shown in Fig. 3, there may be any desired number attached to a mounting or supporting plate 17, one of which unit assemblies may be slipped beneath the bottom 15 of each cube cell. If desired, in lieu of spring assemblies like that shown in Fig. 3 a multiple tempered spring unit 18 may be employed with corrugated spring members 19 attached at their ends to the member 18. This spring unit may be inserted beneath the under side of the bottom of each ice cube cell as shown in Figs. 5 and 7, or if desired instead of utilizing a separate spring unit a tray may be constructed like that of Fig. 8 in which the bottom 20 of each ice cube cell is a spring unit, or in other words a relatively thin spring diaphragm susceptible of flexure.

In accordance with the present invention the tray has certain portions, as for example, its side walls corrugated in order that they may be of relatively thin material but sufficiently stiff and strong to resist distortion by gas under pressure within the hollow portion of the tray. The relatively stiff wall and bottom cause the movable diaphragms or bottoms of the ice cube cells or pockets to receive all of the force from the combined expansion of gas and action of the springs in the gas chamber of the tray.

While in the drawings there appears to be considerable space beneath each of the ice cube cell bottoms 15 or pockets, this space is exaggerated in the drawings to show the construction, actually there being as little space as possible in order to provide a compact structure. With the construction of Fig. 8 there is direct metal to metal contact between the bottoms of the cube cell and the bottom of the tray.

With the construction described the springs 16 of the structure of Fig. 2, the spring portions 19 of the structure of Figs. 5 and 7, and the spring discs 20 of Fig. 8, are all normally urged upwardly under a temperature condition of above 32° so that when the ice cube cells or pockets of the tray are filled with water the bottoms of the ice cube cells or pockets project slightly upwardly into these ice cube cells or pockets. However, upon the temperature being reduced and freezing occurring the bottoms of the cube cells are depressed against the action of the springs and the expandable fluid in the chamber of the tray and remain in this depressed condition until the temperature of the tray is elevated sufficiently that the conjoint action of both the gas pressure and the springs forces the ice upwardly in the pocket in each cell so that it is freed therefrom.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A device of the character described comprising wall structure having a pocket therein for receiving water to be frozen into a unit of ice, the bottom wall of said pocket being deformable, wall structure cooperating with said bottom to form a chamber, a body of fluid confined in said chamber in a manner to exert pressure against said deformable bottom wall upon expansion of fluid due to increase in temperature of the fluid, said chamber forming walls being of a character to transfer heat from an external source to said fluid, and said fluid being of a character and being present in such an amount that upon a rise in temperature of the same that a force will be exerted upon said bottom sufficient to move the same toward the center of said pocket and break the bond between the pocket wall and ice therein, and compression spring means for assisting the expansive action of the fluid in breaking said ice bond.

2. A device of the character described comprising wall structure having a pocket therein for receiving water to be frozen into a unit of ice, the bottom wall of said pocket being deformable, wall structure cooperating with said bottom to form a chamber, a body of fluid confined in said chamber in a manner to exert pressure against said deformable bottom wall upon

expansion of fluid due to increase in temperature of the fluid, said chamber forming walls being of a character to transfer heat from an external source to said fluid, and said fluid being of a character and being present in such an amount that upon a rise in temperature of the same that a force will be exerted upon said bottom sufficient to move the same toward the center of said pocket and break the bond between the pocket wall and ice therein, said bottom wall being provided with means tending normally to urge it toward the center of said pocket thereby supplementing the force by said fluid upon said bottom upon increase in temperature of fluid.

3. In an ice tray having one or more pockets for water to be frozen, and a fluid chamber with a gas in the chamber for absorbing heat and deforming the bottom of the chamber to free the ice in the chamber, and means between and in contact with said deformable bottom and the bottom of said fluid chamber for supplementing the force produced by the expansion of the fluid for freeing the ice.

4. In an ice tray having one or more pockets for water to be frozen, and a fluid chamber with a gas in the chamber for absorbing heat and deforming the bottom of the chamber to free the ice in the chamber, means associated with said deformable bottom for supplementing the force produced by the expansion of the fluid for freeing the ice, said means comprising a compression spring member in said chamber beneath the bottom of the pocket.

5. In an ice tray having one or more pockets for water to be frozen, and a fluid chamber with a gas in the chamber for absorbing heat and deforming the bottom of the chamber to free the ice in the chamber, means associated with said deformable bottom for supplementing the force produced by the expansion of the fluid for freeing the ice, said means comprising a spring plate having a plurality of compressible spring portions adapted to bear against the bottom wall of said pocket.

6. In an ice tray having one or more pockets for water to be frozen, and a fluid chamber with a gas in the chamber for absorbing heat and deforming the bottom of the chamber to free the ice in the chamber, means associated with said deformable bottom for supplementing the force produced by the expansion of the fluid for freeing the ice, said means comprising a spring member in said chamber beneath the bottom of the pocket, said spring member comprising a plate having a plurality of coil springs mounted thereon.

7. In an ice tray having one or more pockets for water to be frozen, and a fluid chamber with a gas in the chamber for absorbing heat and deforming the bottom of the chamber to free the ice in the chamber, means associated with said deformable bottom for supplementing the force produced by the expansion of the fluid for freeing the ice, said means comprising a spring member in said chamber beneath the bottom of the pocket, said spring member comprising a spring plate having a plurality of corrugated spring portions for engagement with the bottom wall of said pocket.

8. A device of the character described comprising wall structure having a pocket therein for receiving water to be frozen into a unit of ice, the bottom wall of said pocket being deformable, wall structure cooperating with said bottom to form a chamber, a body of fluid confined in said

chamber in a manner to exert pressure against said deformable bottom wall upon expansion of fluid due to increase in temperature of the fluid, said chamber forming walls being corrugated at the sides to increase the strength of the walls and the surface area, said walls being of a character to transfer heat from an external source to said fluid, and said fluid being of a character and being present in such an amount that upon a rise in temperature of the same that a force will be exerted upon said bottom sufficient to move the same toward the center of said pocket and break the bond between the pocket wall and ice therein.

9. A device of the character described comprising wall structure having a pocket therein for receiving water to be frozen into a unit of ice, the bottom wall of said pocket being deformable, wall structure cooperating with said bottom to form a chamber, a body of fluid confined in said chamber in a manner to exert pressure against said deformable bottom wall upon expansion of fluid due to increase in temperature of the fluid, said chamber forming walls being corrugated at the sides to increase the strength of the walls and the surface area, said walls being of a character to transfer heat from an external source to said fluid, and said fluid being of a character and being present in such an amount that upon a rise in temperature of the same that a force will be exerted upon said bottom sufficient to

move the same toward the center of said pocket and break the bond between the pocket wall and ice therein, and spring means for assisting the expansive action of the fluid in breaking said ice bond.

- 5 10. A device of the character described comprising wall structure having a pocket therein for receiving water to be frozen into a unit of ice, the bottom wall of said pocket being deformable, wall structure cooperating with said bottom to form a chamber, and including a corrugated side wall extending around three sides of the tray for strengthening and providing increased surface area, a body of fluid confined in said chamber in a manner to exert pressure against said deformable bottom wall upon expansion of fluid due to increase in temperature of the fluid, said chamber forming walls being of a character to transfer heat from an external source to said fluid, and said fluid being of a character and being present in such an amount that upon a rise in temperature of the same that a force will be exerted upon said bottom sufficient to move the same toward the center of said pocket and break the bond between the pocket wall and ice therein,
- 15 20 25 30 said bottom wall being provided with means tending normally to urge it toward the center of said pocket thereby supplementing the force by said fluid upon said bottom upon increase in temperature of fluid.
